(57) CLAIM

The ornamental design for a portion of a wrist band, as shown and described.

DESCRIPTION

FIG. 1 is a perspective view of a portion of a wrist band showing our new design;

FIG. 2 is a front view thereof;

FIG. 3 is a rear view thereof;

FIG. 4 is a left side view thereof;

FIG. 5 is a right side view thereof,

FIG. 6 is a top view thereof; and,

FIG. 7 is a bottom view thereof.

The broken line showing of the circular region on the front, the generally trapezoidal shaped regions on the sides, and the remainder of the wrist band is for illustrative purposes only and forms no part of the claimed design.
